(57) **CLAIM**

The ornamental design for a vehicle grille, as shown and described.

DESCRIPTION

FIG. 1 is a perspective view of the vehicle grille;
FIG. 2 is a left side elevation view thereof (where the right side elevation view is omitted since the right side elevation view is identical to the left side elevation view);
FIG. 3 is a top plan view thereof; and,
FIG. 4 is a front view thereof.

The broken lines in the drawings illustrate portions of the vehicle grille that form no part of the claimed design.
